UNITED STATES PATENT OFFICE.

OTTO J. GROEHN, OF DETROIT, MICHIGAN, ASSIGNOR TO BRISCOE MANUFACTURING COMPANY, OF DETROIT, MICHIGAN, A CORPORATION OF MICHIGAN.

MACHINE FOR BENDING METAL.

1,156,899.

Specification of Letters Patent. Patented Oct. 19, 1915.

Application filed October 22, 1912. Serial No. 727,109.

To all whom it may concern:

Be it known that I, OTTO J. GROEHN, a citizen of the United States of America, residing at Detroit, in the county of Wayne 5 and State of Michigan, have invented certain new and useful Improvements in Machines for Bending Metal, of which the following is a specification, reference being had therein to the accompanying drawings.

10 The invention relates to metal bending machines, and particularly to machines for bending sheet metal strips edgewise to any desired contour.

The invention consists in the means employed for holding the metal from buckling during the bending operation; further in the means for controlling the bending, whereby continuous, changing or reverse curves may be formed as desired; and further in the 20 peculiar construction, combination and arrangement of parts as hereinafter set forth.

In the drawings: Figure 1 is a top plan view of the machine. Fig. 2 is a sectional end elevation thereof. Fig. 3 is a fragmentary view, showing the sheet metal blank as positioned in the rolls; and Fig. 4 is a vertical sectional view of the bending rolls and actuating means.

30 In the manufacture of many articles of sheet metal—as for instance, vehicle mud guards and fenders—it is necessary to provide flanges which are curved in the plane of the sheet. Where such flanges or strips are fashioned by cutting from a sheet metal blank, there is necessarily a considerable waste of material, and furthermore difficulty is experienced in subsequently seaming or beading the curved edges.

With my improved machine such curved 40 strips or flanges may be formed from straight sheet metal blanks, the desired contour being imparted by a bending operation. Also the hooks or flanges preliminary to seaming may be formed in the strip while in 45 the straight, and are not distorted by the subsequent edge bending.

Generally described, my machine comprises a series of pairs of guide rolls for 50 engaging the reverse-bent hooks or flanges on the opposite edges of the sheet metal

blank, one of said pairs being laterally adjustable in the plane of the strip to effect the bend, and its movement being controlled by a cam or pattern, which determines the curve. The adjustable pair of rolls is 55 swiveled to its carrier, permitting said rolls to conform to the varying curvature of the work which is also tangent thereto.

In detail, A is a suitable frame upon which is mounted a longitudinal series of pairs of 60 rolls B B' C C' D D'. Each of these rolls is formed with a flat disk portion F, and having a rounded periphery and an adjacent portion G of smaller diameter having a grooved periphery, the disk portion of one 65 roll of the pair fitting in to the grooved portion of the other roll of the pair. This construction is one adapted for the engagement of a sheet metal blank H, having on the opposite edges thereof the reverse-bent hooks 70 or flanges H' and H'', said return-bends lying between the curved portions and rounded peripheral portions of the rolls, while the flat portion of the blank H'' lies between the flat disk portions of the rolls. 75 Thus when a strip is fed between a pair of such rolls, its opposite edges will be held from inward movement or buckling, even where the strip is subjected to sufficient tension to draw the sheet metal. 80

I I' are the rolls of the laterally-adjustable pair, which are similar in construction and relative arrangement to the rolls B B' C C' etc. These rolls I I' are, however, mounted upon a head member J, which is 85 centrally pivoted to a laterally-slidable head member K mounted in transverse guides L upon the machine.

M M' are roller bearings upon opposite ends of the head member K and which are 90 engaged by complementary pattern-cams N and N' mounted on driven spindles O and O' upon opposite sides of the machine.

P is a stationary cam guide, which engages roller bearings Q Q' upon opposite 95 ends of the swiveled head J, said cam P being so fashioned as to turn the head J to the position indicated by the dotted lines J', to maintain the tangency of the work to the rolls as the head K is laterally adjusted to 100

the position indicated by the dotted lines K' and K² in Fig. 1.

- All of the rolls of the several pairs are preferably driven by a suitable gear-train, indicated in dotted lines at R and R'. The rolls I and I' on the adjustable heads are driven through the medium of a flexibly mounted, telescopic shaft S, which does not interfere with the adjustment of the heads.
- 10 The spindles O O' and cams N N' thereon are driven by gear-wheels T and T' and intermeshing pinions U and U', the gearing being so proportioned that the cams will complete a cycle when the longest length is fed completely through the machine.

In operation, the strips H, which have been previously formed with the opposite return-bent flanges H' H², are fed in between the pairs of rolls, and are advanced thereby until the forward edge engages with the adjustable rolls I I'. The pattern-cams N N' then operate the laterally-slidable head K, and at the same time the stationary cam P, coöperating with the roller bearings Q, Q', will turn the swiveled head J. This shifting of the rolls I I' will cause the bending of the strip, and any buckling of the metal is prevented by reason of the fact that the reverse-bent flanges H' H² are held from inward movement. The shape of the curve imparted to the strip is dependent upon the shape of the cams N N', and by suitably fashioning the latter any form desired may be readily obtained.

35 To adapt the machine for use with strips of varying width the rolls B B', etc., are exchangeable and one member of each pair is mounted in a laterally-adjustable bearing V, positioned by an adjustable stop W. This permits of substituting rolls for wider or narrower strips where the character of the work is changed.

What I claim as my invention is:

1. A machine for bending sheet metal strips in the plane of the main portion thereof, comprising a guide for engaging opposite edge portions of the strip to hold the same from relative inward movement, a second guide similarly formed and engaging the strip, means for feeding the strip through said guides, and coacting means for moving one of said guides laterally with respect to the other guide.

2. A machine for bending sheet metal strips in the plane of the main portion thereof comprising a pair of guides for engaging different longitudinal portions of the strip and holding the opposite edges thereof from relative inward movement, means for feeding the strip through said guides, and coacting means for laterally adjusting one of said guides.

3. A machine for bending sheet metal strips, comprising means engaging the op-

posite edge portions of said strips for holding same from inward movement, means similarly engaging an advanced portion of said strip and laterally adjustable with respect to said first-mentioned means, and coacting means for simultaneously, longitudinally advancing the strip and for adjusting said laterally-adjustable edge-engaging means.

4. A machine for forming sheet metal strips, comprising a guide for engaging the opposite edge portions of a straight strip, an advance guide similarly engaging the edge portion of the strip and laterally adjustable, means for advancing the strip through said guides, and coacting means for laterally adjusting said advance guide and for turning said guide to correspond to the bending of the strip.

5. A machine for bending sheet metal strips, comprising a guide for engaging a straight sheet metal strip, a pair of rolls engaging an advanced portion of said strip and holding the opposite edges thereof from relative movement, means for simultaneously advancing said strip through said guides and for laterally adjusting the advanced guide, and coacting means for turning the axial plane of said rolls to maintain the tangent relation thereof to the portion of the work in engagement therewith.

6. A machine for bending sheet metal strips in the plane of the main portion thereof, comprising a series of rolls for engaging and holding from relative inward movement opposite edge portions of the strip and for advancing the same, and means for laterally shifting one pair of said rolls to effect an edgewise bending of the strip.

7. A machine for bending sheet metal strips, comprising a series of pairs of adjacent disk rolls for engaging opposite flanged edges of the strip and for holding said edges from relative inward movement, a laterally-adjustable head carrying one pair of said rolls, and a pattern-cam operating in timed relation to said rolls for laterally shifting said head.

8. A machine for bending sheet metal strips, comprising a series of pairs of rolls for engaging opposite flanged edges of the strip, a laterally-adjustable head upon which one pair of said rolls is mounted, a swiveled connection between said pair of rolls and said head, permitting a change in angle of the axial plane thereof, a pattern-cam for laterally shifting said head in timed relation to the advance of the strip between said rolls, and a coacting cam for turning the axial plane of said shifted rolls.

9. A machine for forming sheet metal comprising a series of pairs of rolls, each comprising overlapping disks spaced to correspond to the gage of a sheet metal blank

fed therebetween, and concentric laterally-projecting portions on each of said disks forming a rolling surface opposed to the periphery of the overlapping disk for engaging a flanged portion of the sheet metal strip, means for driving said disks to advance the strip, and means for shifting one pair of disks out of alinement with the remaining

pairs of the series to effect the bending of the strip. 10

In testimony whereof I affix my signature in presence of two witnesses.

OTTO J. GROEHN.
